UNITED STATES PATENT OFFICE.

JOHN DILWORTH, OF PIQUA, OHIO, ASSIGNOR TO THE FAVORITE STOVE AND RANGE COMPANY, OF PIQUA, OHIO, A CORPORATION OF OHIO.

GAS STOVE.

Application filed November 7, 1927. Serial No. 231,451.

This invention relates to gas stoves, of the type commonly known as gas ranges, and it seeks to provide a simple and readily manufactured means for providing a plurality of 5 removably mounted cover members, these cover members being adapted to guard the air and gas mixers from heat and dust.

It further seeks to provide such an assembly of cover members which are readily 10 mountable and demountable, the said members being held in frictional engagement with each other.

The invention further seeks to provide a 15 mixer of the type commonly employed in gas stoves of this kind, there being removably mounted upon the mixer a guard member provided with means for protecting the mixer from the heat of the burners, this guard member being provided with means 20 for removably mounting a cover member upon it, the said cover member being adapted to protect the mixer from accumulations of dust and dirt.

The invention further seeks to provide an 25 improved valve operating means for the gas inlets, the said improved means specifically comprising an improved handle for operating the valve, the said handle being, for the purpose of ornamentation, formed preferably of porcelain or an equivalent material which is easily cleaned and which will not alter in color, together with improved means 30 for attaching the said handle to the valve stem.

35 As above indicated, the invention relates to gas stoves of the range type of any style found on the market, there being provided a guard to protect the mixers from the heat of the burner, and a cover member for the 40 mixers mounted upon the said guard.

The invention will be readily understood from an inspection of the accompanying drawings, in which Figure 1 represents a front elevation of a stove to which the present invention has been applied.

Figure 2 is a plan view of such a stove.

Figure 3 is a section taken through the valve and mixer, and showing the means of 50 mounting the valve handle upon the stem, and the cover assembly upon the mixer.

Figure 4 is a view somewhat similar to Figure 3, but showing the cover in position to be applied, but not yet in position.

Figure 5 is a sectional detail view showing

ing the means for securing the cover and 55 the guard together.

Figure 6 shows a detail view of the handle mounted upon the inlet valve, and shows the means for accommodating the cover to the valve stem.

Referring more particularly to the drawings, it will be seen that the stove is indicated generally at 1, and is provided with the customary compartments 2 for carrying out the various cooking operations. The 65 stove is provided with a plurality of burners 3 of the usual type, as usually found in stoves of this type.

Each burner is provided with a mixer for the gas and air, as is customarily employed, 70 the said mixer comprising a gas passage 4 leading to the gas inlet 5. The gas inlet 5 is formed by the valve 6 operated by the stem 6^a and handle 7.

The gas pipe 4 is surrounded by a sleeve 75 8 which is provided with a projection 9, as will be seen from Figure 3, the projection 9 forming a shoulder 10 upon which is sprung the guard member 11, the said guard member being provided with a depending 80 flange or apron 12 serving as the guard proper, and a retaining flange 13 which engages the shoulder 10.

The guard member 11 is slotted, as shown at 14, to receive the hooked projection 15 depending from the cover member 16, the cover 16 being provided with an integral depending flange 17 for engaging the top 90 of the guard member 11. The hooked projection 15, the depending flange 17 and the projection 9 serve to hold the guard member 11 in place. The principal agent in holding the guard 11 in place is the main 4, to which the member 9 is attached. The flange of the guard member 11, extending 95 over the shoulder 10 on the projection 9, prevents the rearward movement of the guard member, while the hook member 15 prevents the lowering of the guard member.

The cover 16 is bent downwardly as at 18 to form the depending portion 19, which is provided with a recess 20 for fitting around the valve stem 6^a. It will thus be seen that the guard member 11 and flange 12 provide a means for protecting the mixer and gas pipe from the heat of the burners, and the cover 16 provides a means for protecting the gas pipe, mixer and valve mechanism from

dust. It will also be observed that the parts are readily detachable, being held in place by frictional engagement between them.

Referring now to the construction of the valve and valve stem, it will be seen that the valve stem 6^a is provided with a pin 21, which pin projects diametrically through the valve stem and is adapted to receive the grooves 22 on the collar 23 of the handle 7.

10 The handle 7 is formed in any ornamental design, the illustration showing the handle to be in approximately the form of a diamond, the handle also being formed of some material which will be permanent in color and easily cleaned. It has been found that porcelain is well adapted for this purpose, and it is frequently desired to form the handle members of such material, the members being either of porcelain, or porcelain enameled as desired.

15 The mixer is shown at 5^a, the gas passing therein through the opening 5^b controlled by the valve 6, the air ports being shown at 6^b. It will be understood that this mixer is of standard construction.

20 The handle 7 is secured to the valve stem at 6^b. It will be understood that this mixer merely attach the handle 7 to the valve stem 6^a and enable it to be detached, if desired. As illustrative of such attaching means, there is shown handle 7 secured to the valve stem 6^a, the stem being threaded and handle is drilled, threaded and screwed on the stem, and is held tightly in position by a small 35 pin pushing through the slot in the handle into a prepared hole in the valve stem.

25 The construction herein described is simple, easily made, sturdy and easily mountable and demountable; its advantages will be obvious to anyone familiar with this art.

30 I desire to comprehend within my invention such modifications as may be clearly embraced within my claims and the scope of my invention.

35 Having thus fully described my invention, what I claim as new and desire to secure by Letters Patent, is:

1. A gas stove comprising the combination with a plurality of burners, of a gas and air mixer for each burner, a gas supply main leading to the mixers, a valve for each mixer controlling the entrance of gas thereto, each valve comprising a stem and handle therefor, a guard member carried by the main and provided with an integral depending flange for protecting the main and valves from the heat from the burners, a cover member carried by the guard member, the said cover extending over and in front of the mixers.

40 2. A gas stove comprising the combination with a plurality of burners, of a gas and air mixer for each burner, a gas main leading into each mixer, a heat-protecting guard member provided with an integral de-

pending guard flange between the mixers and the burners, and a dust-protecting cover for the mixers removably carried by the said guard member, and a valve provided with a valve stem for each mixer, the said cover 70 member extending over and in front of the said mixers and adjacent the said valve stems.

3. A gas stove comprising the combination with a plurality of burners, of a gas and air mixer for each burner, a gas main leading to each mixer, a heat-protecting guard member for the main and mixers and provided with an integral depending guard flange between the mixers and the burners, the said 75 guard member being mounted on the main, a cover member for the mixers removably carried by the guard member and extending over the top and in front of the mixers to protect the same from dust, and a valve for 80 controlling the admission of gas to the mixer.

4. A gas stove comprising the combination with a plurality of burners, of a gas and air mixer for each burner, a gas main 90 leading into each mixer, a valve for each mixer controlling the admission of gas thereto, a heat protecting guard member for the main and mixers provided with an integral depending guard flange between the 95 mixers and the burners, the said guard member being mounted on the main, a cover member for the mixers and valves removably carried by the guard member and extending over the top and in front of the mixers and 100 valves to protect the same from dust.

5. A gas stove comprising the combination with a plurality of burners, of a gas and air mixer for each burner, a main leading into each mixer, a valve for each mixer, 105 and a removable cover assembly for the mixers, valves and main, the said assembly comprising heat and dust guards for the said members.

6. A gas stove comprising the combination with a plurality of burners, of a gas and air mixer for each burner, a main leading into each mixer, a valve for controlling the admission of gas to each of the said mixers, a heat-protecting guard member for the mixers and main, the said guard member being provided with a plurality of slots, a dust-protecting cover member for the mixers, valves and main, the said cover member being removably carried by the said main, the said cover member being provided with projections fitting into the said slots and holding the said cover member in frictional engagement with the guard member, and a valve stem and handle for each valve, 115 120 125 the said cover member projecting downwardly adjacent each of the said valve stems.

7. A gas stove comprising the combination with a plurality of burners, of a mixer for each burner, a gas main leading to each 130

mixer, a valve for each mixer, and a plurality of superposed protective members for the mixers, valves and main.

8. A gas stove comprising the combination with a plurality of burners, of a mixer for each burner, a main leading to each mixer, a valve to control the admission of gas from the main to each mixer, and an assembly comprising a plurality of superposed protective members for the mixers, valves and main, one of the said members of the assembly being removably supported by the other, the said assembly being removably carried by the main.
10. 9. A gas stove comprising the combination with a plurality of burners, of a mixer for each burner, a main leading to each mixer, a valve for controlling the admission of gas from the main to the mixers, a cover assembly for the mixers, valves and main re-

movably mounted upon the main and forming a depending portion having slots, each of the said valves comprising a valve stem filling in a slot, and a handle for said stem.

10. A gas stove comprising the combination with a plurality of burners, of a mixer for each burner, a main leading to each mixer, a valve for controlling admission of gas from the main to each mixer, a cover assembly for the mixers, valves and main and removably mounted upon the main and forming a depending portion having slots, each of the said valves comprising a valve stem and a handle therefor, the valve stem fitting in a slot in the depending portion and handle being provided for turning the stem.

In testimony whereof, I affix my signature.

JOHN DILWORTH.
